AUTOMATIC CLAMP-OPENER THROW-OUTS

William J. Edwards, Stratford, Conn., assignor to The Singer Manufacturing Company, Elizabeth, N. J., a corporation of New Jersey

Application March 8, 1955, Serial No. 492,991

13 Claims. (Cl. 112—110)

This invention relates to cyclically operated sewing machines and more particularly to mechanisms for opening the work-holding clamp of a sewing machine.

It is an object of this invention to provide a novel and efficient throw-out device for an automatic clamp-opening mechanism of the type which derives its motivation from the actuating mechanism of the sewing machine.

It is also an object to provide a means in a cyclically operated sewing machine for selectively varying the duration of the coasting period of the sewing machine at the termination of each cycle of operation.

Still another object of this invention is to provide a throw-out device for an automatic clamp-opener of a cyclically operated sewing machine, which device also serves to effect an increase in the coasting period of the sewing machine when the clamp-opener is thrown out.

With the above and additional objects and advantages in view as will hereinafter appear, this invention comprises the devices, combinations, and arrangements of parts hereinafter described and illustrated in the accompanying drawings of a preferred embodiment thereof in which:

Fig. 1 is a side elevational view of a sewing machine having the side cover-plate of the machine frame removed and portions of the machine bed broken away and illustrated in cross-section to expose the invention applied thereto;

Fig. 2 represents an enlarged vertical cross-section of a portion of the sewing machine taken substantially along line 2—2 of Fig. 1;

Fig. 3 is a bottom view of a portion of the bed of the sewing machine of Fig. 1;

Fig. 4 represents an enlarged elevational view of portions of the clamp-opening mechanism, as illustrated in Fig. 1, with additional parts being broken away and illustrated in cross-section;

Fig. 5 represents a horizontal cross-section of a portion of the automatic clamp-opener throw-out mechanism taken substantially along line 5—5 of Fig. 4, but with the parts being illustrated in proper position for non-automatic or operator influenced operation of the clamp-opening mechanism;

Fig. 5A represents a horizontal cross-section similar to Fig. 5, but with the parts being illustrated in proper position for automatic operation of the clamp-opening mechanism;

Fig. 6 is a fragment of the bottom view of the sewing machine illustrated in Fig. 3, showing the stop-motion latching mechanism in a position corresponding to non-automatic or operator influenced operation of the clamp-opening mechanism; and

Fig. 6A is a view similar to Fig. 6 but showing the stop-motion latching mechanism in a position corresponding to automatic operation of the clamp-opening mechanism.

In sewing machines which are specifically adapted to secure an article to a body fabric as, for instance, in the button sewing machine illustrated in the accompanying

drawings, a work clamp, indicated generally at 11, is employed. The work clamp is provided with a lower jaw portion 12 and an upper button-gripping jaw portion 13 which is pivoted at 14 to the lower jaw so as to provide a hinged and readily releasable clamp for the body fabric and a means for gripping and locating the button with respect to the fabric.

The sewing machine illustrated in the drawings is preferably of a conventional type for this class of article attaching operation in that the machine frame comprises a bed 15 mounted upon a sub-base 16, and a standard 17 from which a bracket arm 18 extends in vertically spaced relation to the bed. A main drive shaft 19 journaled in the bed is arranged, as is well known in the art, to drive both a needle 20 and a looper 21 which is complementary to the needle in the formation of stitches. Also driven by the main drive shaft 19 is a cam shaft 22 which is journaled vertically in the machine frame and has secured for rotation therewith a first pattern cam 23 disposed within the bracket arm 18 and tracked by a follower 24 which serves to jog the needle. A second pattern cam 25 is secured to the cam shaft beneath the bed and is tracked from above by a cam follower 26 which serves to impart jogging movements to the looper complementary to the jogging movements of the needle, and is tracked from below by a cam follower 27 which serves to shift the work clamp bodily along the machine bed. The specific arrangement of cam followers is well known in the art and serves to provide a machine 30 in which the needle and the looper are jogged to stitch alternately through a first pair of holes in a button and in which the work clamp is shifted to present a second pair of holes to the stitch-forming instrumentalities.

The upper jaw portion 13 of the work clamp is normally biased downwardly into closed work gripping relation with the lower jaw portion by means of a presser-bar 29 endwise slidable in the bracket arm. The lower extremity of the presser-bar is disposed in engagement with the upper jaw portion and is biased downwardly by a coil spring 30 seated against an adjusting screw 31 accessible from the top of the bracket arm for changing the spring pressure operative to maintain the work clamp in closed position.

In order to effect opening of the work clamp in opposition to the coil spring 30, a link 32 is arranged between the upper jaw 13 of the clamp and a rock arm 33 of a clamp-opening rock shaft 34 journaled in the bracket arm. The clamp-opening rock shaft is controlled by means of a push rod 35 journaled vertically in bearing bushings 36, 36 in the machine standard. A rock arm 37 and a link 38 serve to interconnect the push rod 35 with the clamp-opening rock shaft 34.

As is customary in article attaching sewing machines of the type disclosed in the drawings, stop-motion mechanism is provided for rendering the operation thereof cyclic. In the drawings, a stop-motion mechanism is illustrated of the type disclosed in the copending patent application of R. D. Sweet and W. J. Edwards, Serial No. 413,228, filed March 1, 1954, to which reference may be had for a detailed description thereof. The stop-motion mechanism will be described here only to the extent necessary for a complete understanding of the present invention.

The motion necessary to drive the sewing machine is delivered from any conventional source of power by means of a V belt 39 which engages a two-part separable pulley having an inner pulley portion 40, which is fixed for rotation with the main drive shaft 19, and an outer pulley portion 41, which is freely journaled on the main drive shaft and which is free to move axially thereof. The loose outer pulley portion 41 may be urged inwardly

so as to compress and pinch the side of the V belt frictionally against the fast inner pulley portion so that the belt will drive the sewing machine main shaft. Similarly, when the force urging the loose outer pulley portion inwardly is discontinued, the V belt will ride idly upon the outer loose pulley portion and the transmission of power to the sewing machine will be interrupted. In order to control the loose outer pulley portion 41, a swinging stop-motion frame 42 is pivoted at 43 to lugs 44 extending outwardly from the sewing machine standard. The stop-motion frame depends from the pivot 43 and has fixed thereto a substantially horizontal operating arm 45. The frame 42 loosely embraces the main drive shaft 19 and terminates in a downwardly and laterally extending arm 46 which, as will be described in detail later, serves to control the automatic clamp-opening mechanism. Riveted to the stop-motion frame near the pivot 43 is a relatively flat spring member 47 which extends downwardly and into axial engagement with an antifriction thrust bearing ball 48 journaled at the outer extremity of the loose outer pulley portion. The spring member 47 is embraced and stiffened by a support member 49 which extends from the swinging frame. Movement of the swinging frame will thus serve to control the transmission of power to the sewing machine.

The swinging frame 42 also serves to bring the sewing machine to a definite predetermined at-rest position and to lock the machine in this position until initiation of a succeeding cycle of operation. To this end, a rod 50 is journaled for endwise movement vertically in a lug 51 formed to extend from the stop-motion frame. The rod is resiliently centered with respect to the lug by means of coil springs 52 and 53 and is provided at its lower extremity with a stop block 54 which cooperates with a notched stop cam formed on the sub 55 of the fast inner pulley portion 40. Thus, after the stop-motion frame is turned so that the loose pulley portion becomes free on the main drive shaft and the power to the sewing machine is discontinued, further movement of the stop-motion frame will bring the stop block into engagement with the notched stop cam and the machine will be brought to a cushioned stop in a definite position determined by the position of the stop cam on the main drive shaft.

The automatic clamp-opening mechanism, as best illustrated in Figs. 1, 2 and 3, is patterned after that forming the subject of the copending U. S. patent application of R. D. Sweet and W. J. Edwards, Serial No. 466,034, filed November 1, 1954, to which reference may be had for a complete description thereof. The automatic clamp-opening mechanism will now be described to the extent necessary for a clear understanding of the present invention.

Disposed to engage the depending free end of the clamp opening push rod 35 is the horizontal arm 56 of a bell crank lever 57 fast upon a stud shaft 58 which is journaled for both turning and sliding movements in a boss 59 formed in the bed 15. A vertical follower arm 60 of the bell crank is urged by a coil spring 61 into engagement with a clamp-opening cam member 62 which is fast on the sewing machine main drive shaft 19. The cam member 62 is formed with a substantially cylindrical hub portion 63 from one side of which rises a cam lobe 64. A coil spring 65 restrained between the bed 15 and an enlarged head 66 formed on the stud shaft 58 serves to bias the stud shaft and the bell crank 57 fixed thereto to the right, as viewed in Fig. 1, and into a position determined by a stop screw 67 threaded into the lateral arm 46 of the stop-motion controlling frame 42. During operation of the machine, the bell crank 57 is shifted to the left, as viewed in Figs. 1 and 3, by the lateral arm 46 and the vertical follower arm 60 of the bell crank is maintained in engagement with the substantially cylindrical hub portion 63 of the cam 62. When the stop-motion frame is released and moves into the stopped position of Figs. 1, 2 and 3, the bell crank 57 is free to move to

the right in a position in which the follower arm 60 will be acted upon by the cam lobe 64 to actuate the push rod 35 and open the work clamp.

Carried above the bed 15 within the standard and as illustrated in Fig. 5A, is a latch lever 68 urged by a coil spring 69 toward the push rod 35. The push rod is notched, as at 70, so as to accommodate the latch lever 68 when the push rod is shifted to open the clamp. The latch lever 68, therefore, assumes from the bell crank 57 the burden of the clamp-closing spring 30 as well as a return spring 71 on the push rod 35, thus freeing the clamp-opening bell crank 57 for comparatively effortless axial shifting movement upon initiation of a succeeding cycle of operation. A trip finger 72 fixed to depend from the actuating arm 45 of the stop-motion frame 42 is disposed to engage an upturned lug 73 on the latch lever 68 to shift the lever out of the notch 70 in the push rod as a succeeding cycle of stitches is initiated.

The present invention provides a device for throwing out of operation the automatic clamp-opening mechanism so that, whenever it is so desired, the work clamp may be opened and closed by manual or other operator influenced means.

The throw-out mechanism, which is best illustrated in its entirety in Figs. 2 and 4, is operated by a lever 75 secured by a pivot screw 76 atop the machine bed and having an operating handle 77. A pair of bell crank levers 78 and 79 are pivoted inside the machine bed by pivot screws 80 and 81, respectively, and are interconnected by means of a pin 82 carried by the lever 79 and a pin-accommodating slot 83 formed in the lever 78. An upstanding arm 84 of the lever 78 is bifurcated and disposed to extend through an opening 85 in the bed and to embrace the throw-out lever 75, while the depending arm 86 of the lever 79 is disposed within a transverse slot 87 formed in the boss 59 in which the stud shaft 58 for the automatic clamp-opening bell crank is journaled. The stud shaft 58 is formed with an annular groove 88 disposed to occupy a position in alignment with the transverse slot 87 in the boss when the sewing machine is operating and the clamp-opening bell crank 57 is shifted out of operative position in the path of the clamp-opening cam lobe 64. The depending arm 86 of the lever 79 may be shifted in response to movement of the operating handle 77 to a position within the annular groove 88 of the stud shaft 58 in order to latch the clamp-opening bell crank into this inoperative position.

In Fig. 5, the lever 75 is illustrated in position for manual operation of the clamp-opening linkage, while Fig. 5A represents the same view with the parts being disposed in positions corresponding to automatic operation of the clamp-opening mechanism.

The lever 75 is joined by an arm 89 which is adapted to engage the latch lever 68. As illustrated in Fig. 5, when the parts are positioned for manual opening of the clamp, the arm 89 holds the latch lever 68 out of engagement with the notch 70 of the push rod 35. The work clamp, therefore, will not be latched in open position when the automatic clamp-opening mechanism is thrown out of operation and, consequently, the operator will have direct control over both the opening and the closing of the work clamp.

As best illustrated in Figs. 2 and 3, the mechanism by which the work clamps may be controlled under the influence of the operator comprises a bell crank 91 which is pivoted on a bracket 92 carried by the sub-base 16 of the machine. The bell crank 91 is formed with an offset finger 93 which is disposed to underlie the horizontal arm 56 of the automatic clamp-lifting bell crank lever 57, and is provided with a pull chain 94 which may be connected with any suitably arranged treadle or knee shifter. A spring 95 is associated with the bell crank 91 and serves to bias the offset finger 93 into an extreme lowered position against the sub-base 16 so that when the bell crank 91 is idle, the offset finger 93 will not

interfere with operation of the automatic clamp-opening bell crank lever 57.

The mechanism for controlling the stop-motion frame so that the machine may be started at the will of the operator and brought to a stop after a predetermined number of stitches have been made, as best illustrated in Figs. 1 and 4, comprises a link 97 pivoted to the actuated arm 45 of the stop-motion frame and to a slide rod 98 which is journaled vertically in the machine bed. A bell crank 99 carried by the sub-base 16 of the machine is adapted to be operated by the machine operator by means of a pull chain 100, and bears beneath the slide rod 98 so as to shift the stop-motion frame in a clockwise direction, as viewed in Fig. 1, in opposition to a coil spring 101 between the machine standard and the stop-motion frame to initiate a cycle of stitches.

The stop-motion frame is maintained in running position during the cycle of stitching operation by means of a latch arrangement between a sleeve 102 which loosely embraces the slide rod 98 and a latch lever 103. The sleeve 102 is tapped to receive set screws such as that illustrated at 104 which project into an annular groove 105 formed in the slide rod, thereby to lock the sleeve for axial movement with the slide rod while providing for freedom from rotational movement of the sleeve with respect to the slide rod.

The lower extremity of the sleeve 102 is formed with stepped substantially concentric portions 106 and 107 defining shoulders 108 and 109, respectively, in substantially parallel planes spaced axially along the sleeve 102. The end portion 107 of the sleeve is notched, as at 111, which serves, as is best illustrated in Figs. 6 and 6A, to provide a widened portion 108A of the shoulder 108 and a correspondingly narrowed portion 109A of the shoulder 109.

The latch lever 103 is fast on a rock shaft 112 journaled transversely of the machine bed 15 and is formed with a substantially vertical arm 113 terminating in a latch finger 114 which is movable readily with respect to the slide rod 98 in a path traversing the shoulders 108 and 109 of the sleeve 102. A substantially horizontal arm 115 of the latch lever 103 is formed with a trip finger 116 disposed for engagement with a cam plate 117 secured by screws 118—118 to the periphery of the pattern cam 25 within the machine bed. A coil spring 119 urges the latch lever 103 in a clockwise direction.

The bottom edge of the cam plate 117 is stepped to provide three cam surfaces 120, 121 and 122 disposed in parallel planes which are evenly spaced axially with respect to the pattern cam 25. In Fig. 1, the sewing machine is illustrated in stopped position and the trip finger 116 is in engagement with the cam surface 120, in which position the latch finger 114 is shifted beyond the periphery of the concentric portion 106 of the sleeve 102, thus freeing the sleeve 102, the slide rod 98 and the stop-motion frame for movement in response to the coil spring 101 into the stopped position. In order to start the sewing machine upon a succeeding cycle of stitches, the sleeve 102 and the slide rod 98 are raised by manual actuation of the bell crank 99. As the main drive shaft and, consequently, the pattern cam shaft 22 begin to turn, the cam plate 117 moves toward the right, as viewed in Fig. 1, and the cam surface 120 is shifted out of engagement with the trip finger 116, thus releasing the latch lever 103 for movement in response to spring 119 to a position in which the latch finger underlies the shoulder 109 of the sleeve 102, thus locking the sewing machine actuating mechanism in running position for one cycle of rotation of the pattern cam 25, i. e., until the cam surface 120 again moves into engagement with the trip finger 116 of the latch lever.

Since the cam plate 117 is provided with stepped cam surfaces 120, 121 and 122, the latch lever 103, at the completion of each cycle of machine operation, will be shifted in three stages to release the sleeve 102 and the

slide rod 98 to stop the machine. As stated above, the latch finger 114 of the latch lever is disposed in engagement with the shoulder 109 during operation of the sewing machine. As the latch finger 114 is shifted outwardly 5 away from the slide rod 98, it moves beyond the shoulder 109 bringing the shoulder 108 into engagement with the latch finger and thus partially releasing the sleeve 102 and the slide rod 98 so as to discontinue the transmission of power to the sewing machine. The sewing machine 10 then coasts until the latch lever 103 is shifted an additional amount to the position as shown, for instance, Fig. 4 in which the latch finger is moved outwardly beyond the shoulder 108 of the sleeve 102 thus completely freeing the stop-motion frame 42 and rendering the positive 15 stop-motion mechanism operative.

The automatic clamp-opener throw-out lever 75 is formed with an upturned bifurcated arm 123 which embraces a pin 124 extending radially from the sleeve 102 so that as the throwout lever 75 is turned from a position 20 corresponding to manual operation of the clamp opener, as shown in Fig. 5, to a position corresponding to automatic clamp opening, as shown in Fig. 5A, the sleeve 102 will be turned from a position in which the notch 111 overlies the path of movement of the latch-finger 114, as shown in Fig. 6, to a position in which the notch 111 is disposed entirely at one side of the path of movement of the latch finger, as illustrated in Fig. 6A.

The stepped cam surfaces 120, 121 and 122 and the angularly adjustable sleeve 102 provide a means for varying 30 the period during which the machine will coast, i. e., the time increment between that at which the transmission of power is interrupted and that at which the machine reaches its definite stopped position. Of the many possible advantages of a means for varying the coasting 35 period of a sewing machine, one illustrated in the preferred embodiment of the drawings is that the machine may thereby be adjusted to operate smoothly and at a fixed maximum operating speed whether or not the automatic clamp-opening mechanism is used. The automatic 40 clamp-opening mechanism utilizes for its operation the momentum of the sewing machine actuating mechanism while it is coasting to a stopped position. When the automatic clamp-opening mechanism is rendered inoperative, it is advantageous to increase the coasting period so as to dissipate in coasting the added increment of kinetic 45 energy no longer drawn off by the clamp opener. By lengthening the coasting period under these circumstances, strain on the stop-motion mechanism ordinarily cushioned by the clamp-opening mechanism, is correspondingly reduced. 50

Operation of the means for varying the coasting period is indicated in Figs. 6 and 6A, in both of which the trip finger 116 of the latch lever 103 is disposed in engagement with the first step 122 of the cam plate 117. In 55 Fig. 6 which illustrates the position of the sleeve 102 corresponding to manual operation of the clamp opener, the notch 111 is disposed so as to be intersected by the path of the latch finger 114 of the latch lever 103. Latch finger 114 thus traverses the narrow portion 109A of the shoulder 109 so that the increment of latch movement occasioned by the first cam surfaces 122 causes the finger 114 to release the shoulder 109 and take up a position in engagement with the widened portion 108A of the shoulder 108 in which position of parts the transmission of power to the sewing machine will be interrupted and the machine will coast. As the succeeding cam surface 121 60 engages the trip finger 116, the latch finger 114 merely moves radially along the widened portion 108A of shoulder 108 and the coasting continues until the cam surface 121 65 shifts the latch finger 114 completely beyond the sleeve 102, as illustrated in Fig. 4.

In Fig. 6A, the parts are illustrated in position corresponding to automatic operation of the clamp-opener. The notch 111 of shoulder 109 is turned out of the path 75 of the latch finger 114 so that the normal width of the

shoulder 109 is presented to the latch finger. With this position of parts, engagement of the initial step 122 of the cam plate 117 with the trip finger 116 merely moves the latch finger 114 radially along the shoulder 109 to the position illustrated in Fig. 6A and does not interrupt transmission of power to the sewing machine. The succeeding cam step 121, however, does shift the latch finger 114 opposite the sleeve shoulder 108 to initiate the shortened coasting period.

From the foregoing description considered in connection with the accompanying drawings, the construction, manner of operation and several advantages of our automatic clamp-opener throw-out will be clearly and fully understood. It is apparent that the devices have a wide variety of uses, and it will be understood that the form, construction and arrangement of the several elements employed may be varied. Therefore, the privilege is reserved of resorting to all such legitimate changes therein as may be fairly embodied within the spirit and scope of the appended claims.

Having thus set forth the nature of the invention, what I claim herein is:

1. In a cyclically operated sewing machine having a drive means and a stop motion mechanism for stopping said sewing machine at a definite predetermined point in a sewing cycle, means for interrupting said drive means prior to said predetermined point comprising a control latch adapted to maintain said drive means in operative driving relation with said sewing machine, a plurality of latch releasing means operated by said sewing machine each being capable of tripping said latch to interrupt said drive means at a different interval prior to said predetermined point, and means rendering effective a selected one of said latch releasing means.

2. In a cyclically operated sewing machine, driving means therefor, a control member associated with said driving means and having a position effective to render said driving means operative and a position effective to interrupt said driving means, a latch member movable in one direction to maintain said control member in a position in which said driving means are operative, means operated by said sewing machine for shifting said latch member in the opposite direction in a plurality of successive increments during the operation of the sewing machine, and means for effecting movement of said control member to a position interrupting said driving means on any selected one of said plurality of successive increments of latch movement.

3. In a cyclically operated sewing machine having driving mechanism, means for interrupting said driving mechanism prior to completion of each cycle of machine operation, a work-gripping clamp and clamp-opening mechanism operated by said sewing machine, the combination of operator controlled mechanism for throwing said clamp-opening mechanism into and out of operation, and means under control of said operator controlled mechanism for altering the timing of said interrupting means.

4. In a cyclically operated sewing machine having driving mechanism, means for interrupting said driving mechanism prior to completion of each cycle of machine operation, a work-gripping clamp, and a clamp-opening mechanism operated by said sewing machine, means simultaneously rendering said clamp-opening mechanism inoperative and advancing the timing of said interrupting means.

5. In a sewing machine having a driving mechanism, a stop-motion mechanism therefor, means for interrupting said driving mechanism to provide for a coasting period prior to operation of said stop-motion mechanism, normally inoperative mechanism appurtenant to said sewing machine, operating means adapted to harness the inertia of the sewing machine during said coasting period to operate said appurtenant mechanism, throw-out mechanism under control of the sewing machine operator for

rendering said operating means selectively operative or inoperative, and means under control of said throw-out mechanism for selectively varying said coasting period.

6. In a sewing machine having a work-gripping clamp, clamp-opening mechanism carried by said sewing machine, actuating means for said clamp-opening mechanism driven by said sewing machine, and a member movable bodily into and out of an operative position between said clamp-opening mechanism and said actuating means, a latch device carried by said sewing machine and adapted to engage and to lock said member into an inoperative position, and a manually operable latch-controlling lever carried by said sewing machine.

7. In a sewing machine having a work-gripping clamp, clamp-opening mechanism carried by said sewing machine including a clamp-opening push rod journaled therein, actuating means for said clamp-opening mechanism including a cam driven by said sewing machine, a lever pivoted in said sewing machine and bodily movable lengthwise of its pivotal axis into and out of an operative position between said push rod and said actuating cam, and latch means under control of the sewing machine operator for locking said lever in an inoperative position lengthwise of its pivotal axis.

8. In a sewing machine having a work-gripping clamp, clamp-opening mechanism carried by said sewing machine, actuating means for said clamp-opening mechanism driven by said sewing machine, and operating lever carried by a fulcrum rod which is journaled for turning and for axial movements in said sewing machine, said lever and fulcrum rod being movable axially to shift said lever into or out of operative position between said clamp-opening mechanism and said actuating means, and clamp-opener throw-out means comprising a latch lever carried by said sewing machine and disposed to engage and lock said fulcrum rod in an axial position in which said operating lever is in inoperative position, and a manually operable member carried by the sewing machine for controlling said latch lever.

9. In a sewing machine including an actuating mechanism and a stop-motion mechanism having two extreme positions, one in which power is transmitted to the sewing machine actuating mechanism and one in which motion of the actuating mechanism is arrested and an intermediate position in which transmission of power is interrupted but the actuating mechanism is free to coast, means for controlling said stop-motion mechanism comprising a keeper member operatively connected with said stop-motion mechanism and confined to movement on said sewing machine into any one of two extreme positions or an intermediate position corresponding to the three positions of said stop-motion mechanism, a latch member shiftably supported on said sewing machine and disposed for movement into and out of the path of movement of said keeper member, latch shifting means associated with said sewing machine actuating mechanism, one of said stop-motion controlling members being provided with an element defining at least two differently dimensioned sets of stepped surfaces of which each step corresponds to one of said three stop-motion mechanism positions, and operator controlled mechanism on said sewing machine operatively connected to shift said element to present a selected one of said sets of surfaces for interengagement with the other of said stop-motion members.

10. In a sewing machine including an actuating mechanism and a stop-motion mechanism having two extreme positions, one in which power is transmitted to the sewing machine actuating mechanism and one in which motion of the actuating mechanism is arrested and an intermediate position in which transmission of power is interrupted but the actuating mechanism is free to coast, means for controlling said stop-motion mechanism comprising a keeper member operatively connected with said stop-motion mechanism and confined to movement on said sewing machine into any one of two extreme positions or an

intermediate position corresponding to the three positions of said stop-motion mechanism, a latch member shiftably supported on said sewing machine and disposed for movement into and out of the path of movement of said keeper member, means associated with said sewing machine actuating mechanism and effective to shift said latch member in a plurality of substantially equal increments to a position out of operative engagement with said keeper member, an element carried by said keeper member and formed with at least two sets of stepped surfaces, each step corresponding to one of said three stop-motion mechanism positions, said element being shiftably supported with respect to said keeper member, operator controlled mechanism on said sewing machine operatively connected to position a selected one of said sets of stepped surfaces for traversal by said latch member, said sets of stepped surfaces differing as to the length along the path of traversal by said latch member of that surface corresponding to the intermediate or coasting position of the stop-motion mechanism, thereby providing for a selective variation of the number of increments of latch movement during which the sewing machine will coast.

11. In a sewing machine having an actuating mechanism and a stop-motion mechanism including a shiftable stop-motion frame having two extreme positions, one in which power is transmitted to the sewing machine actuating mechanism and one in which motion of the actuating mechanism is arrested and an intermediate position in which transmission of power is interrupted but the actuating mechanism is free to coast, means for controlling said stop motion frame to vary the coasting period comprising a slide rod journaled with respect to said sewing machine, operative connections between said slide rod and said stop-motion frame, a sleeve journaled for turning movement on said slide rod, means securing said sleeve against movement axially with respect to said slide rod, a plurality of sets of radially extending stepped latch surfaces formed on said sleeve, each of said surfaces corresponding to one of said stop-motion frame positions

and each of said sets of surfaces differing in the radial dimension of at least one of said surfaces, a latch lever carried by said sewing machine, a latch finger carried by said lever and disposed to move in a path traversing radially of said sleeve, means under control of said sewing machine actuating mechanism for tripping said latch lever in a plurality of successive increments, and operator influenced means for turning said sleeve to position a selected one of said sets of stepped latch surfaces in the path of said latch finger.

12. In a sewing machine as set forth in claim 11, a work-gripping clamp, clamp-opening mechanism carried by said sewing machine, an operating means for said clamp-opening mechanism driven by said sewing machine actuating mechanism, a member movable bodily into and out of operative position between said clamp-opening mechanism and said operating means therefor, a latch device carried by said sewing machine and adapted to engage and to lock said member into an inoperative position, said latch device being under control of said operator influenced means for turning said sleeve.

13. In a cyclically operated sewing machine having a drive means, stop motion mechanism for stopping said sewing machine at a definite predetermined point in a sewing cycle, means for interrupting said drive means before the sewing machine reaches said predetermined point to provide a coasting period, mechanism for selectively advancing or retarding the point in the cycle at which said interrupting means is operated to vary the coasting period, and means under control of the sewing machine operator for actuating said mechanism.
